(57) CLAIM

The ornamental design for a jacket, as shown and described.

DESCRIPTION

FIG. 1 is a front perspective view of a jacket showing the claimed design;

FIG. 2 is a front view thereof;

FIG. 3 is a rear view thereof;

FIG. 4 is a left side view thereof;

FIG. 5 is a right side view thereof; and,

FIG. 6 is a rear perspective view thereof.

The dashed broken lines in the figures show stitching that form part of the claimed design.

Portions of the jacket that are not shown form no part of the claimed design.
